CLAIM

The ornamental design for a vehicle display screen with graphical user interface, as shown and described.

DESCRIPTION

FIG. 1 is a front view of a first embodiment of a vehicle display screen with graphical user interface;

FIG. 2 is a front view of a second embodiment thereof;

FIG. 3 is a front view of a third embodiment thereof; and,

FIG. 4 is a front view of a fourth embodiment thereof.

The dashed broken line showing of the vehicle display screen forms no part of the claimed design. The dot dashed broken lines showing portions of the graphical user interface form no part of the claimed design.
